UNITED STATES PATENT OFFICE.

VITTORIO BOSCAVILLA, OF SAN FRANCISCO, CALIFORNIA.

SUBMERSIBLE APPARATUS.

1,260,959.

Specification of Letters Patent. Patented Mar. 26, 1918.

Application filed February 9, 1916. Serial No. 77,242.

To all whom it may concern:

Be it known that I, VITTORIO BOSCAVILLA, a citizen of the United States, residing at San Francisco, in the county of San Francisco and State of California, have invented new and useful Improvements in Submersible Apparatus, of which the following is a specification.

This invention relates to a submersible apparatus, designed to serve the function of a diving bell, whereby submarine explorations may be readily and conveniently carried out.

One object of the invention is to provide a submersible apparatus which may be sunk to any reasonable depth by the ordinary process of weighting it with water, and which embodies a chamber or lock normally serving as a water ballasting chamber, and which affords communication between the interior of the vessel or apparatus and the water whereby a diver may pass in or out of the apparatus at will.

A further object of the invention is to provide a submersible apparatus which embodies novel and improved means for the admission of the water for ballasting purposes, the discharge of the water for lightening the apparatus to bring it to the surface, and for trimming the apparatus during the operation of opening and closing the outer door of the diver's lock or chamber, by means of which the apparatus may be maintained in an upright and balanced position at all times.

A still further object of the invention is to provide a strong and durable type of apparatus which is capable of resisting great pressures and may be submerged to a great depth, and which at the same time may be rapidly and conveniently lightened to bring it to the surface or to increase its buoyancy to any degree desired at will.

The invention consists of the features of construction, combination and arrangement of parts herein fully described and claimed, reference being had to the accompanying drawings in which:

Figure 1 is a top plan view of a submersible apparatus embodying my invention.

Fig. 2 is a central vertical transverse section through the apparatus as it appears when at the surface.

Fig. 3 is a similar view of the apparatus as it appears when submerged to a desired depth.

Fig. 4 is a view on an enlarged scale through the portion of the apparatus containing the diver's lock, showing the same as it appears when the inner door is open to afford communication between the lock and the main room or compartment of the apparatus.

The submersible apparatus embodying my invention comprises a hollow body or vessel 1 of any suitable size and internal area or capacity. This vessel 1 comprises a generally oblong body portion 1 having a scow-shaped bottom 2, and a substantially circular dome-shaped top portion 4, the vessel 70 being made of structural steel or metal of material strength and capacity to resist strains, whereby the apparatus is rendered capable of being submerged to a great depth without danger of collapse. As shown, the apparatus is provided at its top with a cock pit 5 adapted to be hermetically sealed by a door or closure 6. This closure may be removable or not, and is provided with an opening 7 closed by a door or lid 8, which opening affords a doorway for the ingress and egress of the crew, passengers, etc. The railing 9 extends upward from the cock pit 5 and closure 6, and provides with said closure, which forms a floor surface, a deck or 85 conning tower for an obvious purpose.

A horizontal partition 10 separates the interior of the receptacle into upper and lower compartments 11 and 12. The upper compartment 11 may serve as officers' quarters, 90 containing registration and indicating instruments, etc., together with means for the storage of provisions and supplies, if desired, while the lower compartment 12 may serve as quarters for the crew and also as 95 an engine room, in which pumps and other appliances may be arranged. A ladder or other stair structure 13 extends through the floor 10 and leads from the compartment 12 upward through the compartment 11 to the 100 cock pit, for the convenience of those entering and leaving the vessel and passing between the compartments. In practice, any suitable means for storing and admitting fresh air to the compartments, as well as 105 for purifying foul air, may be employed.

In the present instance I have shown the bottom 2 of the receptacle provided on opposite sides of its longitudinal center with water receiving and ballasting tanks 14 and 110 14', which tanks may be of sufficient capacity when filled to weight the apparatus

to the degree to submerge it to any required depth. Water containing compartments or tanks 15 and 16 are formed on opposite sides of the compartment 12 and separated therefrom by walls or partitions 17 and 18. These compartments 15 and 16 are of like capacity, and are designed to receive bodies of water for certain specified purposes. The said compartments are in communication 10 with superposed air chambers 19 and 20, which also may communicate with the lower ballasting tanks 14 and 14' whereby the water compartments and tanks are adapted to be filled and emptied without atmospheric resistance, air being permitted to enter to take the place of the discharging water or to pass out into the air containing compartments when the tanks or compartments are filled with water.

20 An electric pump 19, preferably of the double acting type, and driven by storage batteries, is arranged within the engine room or compartment 12, the inlet connections of this pump are in communication with the 25 respective tanks and water compartments through a series of valved water discharge pipes 20', and with a water inlet main or supply pipe 21, while the outlets of the pump are in connection with valved water 30 feed pipes 21', leading to the water containing tanks and compartments and with a valved outlet pipe 22 leading to the exterior. The valves in these pipes are so arranged that communication may be established between any one or all of the tanks or compartments and the inlets of the pump for the purpose of discharging the water from said tanks or compartments, or communication can be established between the 35 inlets of the pump and exterior through the supply pipe 21, and from the outlets of the pump to the tanks or compartments so that a supply of water from the body of water in which the apparatus floats or is submerged may be supplied to fill the respective tanks or compartments to desired degrees. Furthermore, by suitably opening and closing valves in the pipes, communication may be established between the inlets of the 40 pump and one or all of the respective tanks or compartments and the outlet pipe 22, for the purpose of discharging the water from said tanks or compartments to the exterior, for the purpose of trimming the craft or reducing the same of the weight of more or less of the water to cause it to rise to a greater or less degree toward the surface after submergence.

50 The compartment 16 comprises a diver's lock or chamber, having a door 23 giving access to the compartment 12 and a door 24 giving access to the exterior of the vessel and affording communication between the said compartment 16 and the body of water outside. Hence it will be understood that

when it is desired to send a diver out to make explorations, this may be done by opening the door and allowing the diver, properly equipped in advance, to pass into the compartment 16, after which both compartments 15 and 16 are filled with water, the compartment 16 being filled to make the pressure therein equal to that of the outside pressure when the door 24 is opened, while the compartment 15 is filled to trim the 70 craft so that it will be balanced in a lateral direction. After the diver has entered the compartment 16 and the door 23 has been closed and said compartment 16 filled with water, the door 24 is opened, allowing the 75 diver to pass out for the purpose of making the desired explorations, it being understood that suitable provision will be made for the supply of air to the diver from the interior of the craft in any suitable manner.

85

When the diver finishes his work and wishes to return, he passes through the doorway 24 back into the compartment 16 and closes the doorway 24, and then suitably notifies those within the compartment 12 of 90 his presence in the compartment 16, the condition of affairs therein and his intention to open the door 23 and enter the compartment 12. His intention being understood the pump is set into action to exhaust the water 95 from the compartments 15 and 16, and when this has been accomplished the door 23 is opened, allowing the diver to enter the compartment 12, as will be readily understood.

In practice, the tanks 14 and 14' give 100 stability and may be of such capacity as to weight the vessel, when they are filled, to cause it to descend to the maximum depth desired, but other ballasting or weighting tanks or compartments, in addition to the 105 compartments 15 and 16, may be provided at suitable points. The compartments 15 and 16, it will be understood, furnish a means by which a diver may be sent out while the craft is submerged to carry on 110 different operations below the level of the water, while the vessel is maintained in an upright or balanced position, thus insuring stability under all conditions of service.

I claim:—

115

1. A submersible apparatus of the diving class comprising a main shell provided with spaced compartments, certain of which form a trimming tank and a diver's lock, a self-contained mechanical operating plant in one 120 of said compartments, and means to cooperate with said plant for controlling the buoyancy of the apparatus through an interchange of the contents of the tank and lock, which interchange also operates to produce 125 a stable equilibrium when a diver enters and leaves the lock.

2. A submersible apparatus of the diving class comprising a main shell provided with spaced compartments, certain of which form 130

a trimming tank and a diver's lock, water ballast compartments disposed at the bottom of the shell, a self-contained operating plant in one of said compartments, and means to coöperate with the mechanical plant for controlling the buoyancy of the apparatus through an interchange of the contents of the tank, lock and water ballast compartments, which interchange also operates to produce a stable equilibrium when a diver enters and leaves the lock.

3. A submersible apparatus of the diving class comprising a main shell provided with vertical and horizontal wall forming compartments, a mechanical operating plant in one of said compartments, another of said compartments being subdivided and disposed at the bottom of the shell while others are disposed above the latter and form respectively a trimming tank and the diver's lock, the horizontal walls forming floors or platforms that subdivide the interior of the shell into working spaces, one of which is

disposed above the compartment carried at the bottom of the tank that provides a place for the mechanical operating plant, an exit for the diver's lock so disposed as to permit the diver to pass into and out of the shell through one of the vertical walls of said shell, and means to coöperate with said plant for controlling the buoyancy of the apparatus through an interchange of the contents of the tank, lock, and the several compartments, which interchange also operates to produce a stable equilibrium when the diver enters and leaves the lock, said means being so connected that interchange between the several compartments and the tank and lock may be made singly or in combination.

-In testimony whereof I affix my signature in presence of two witnesses.
